DESIGN FOR A THERMOMETER MOUNTING BRACKET

Charles W. Brant, Dayton, Ohio, assignor to
General Motors Corporation, Dayton, Ohio, a
corporation of Delaware

Application October 26, 1936, Serial No. 65,510

Term of patent 14 years

To all whom it may concern:

Be it known that I, Charles W. Brant, a citizen of the United States, residing at Dayton, in the county of Montgomery and State of Ohio, have invented a new, original, and ornamental Design for a Thermometer Mounting Bracket of which the following is a specification, reference being had to the accompanying drawing, forming part thereof.

In the drawing:

Fig. 1 is a perspective front view of the thermometer mounting bracket showing my new design;

Fig. 2 is a top plan view of the mounting bracket;

Fig. 3 is an end elevational view of the mounting bracket;

Fig. 4 is a sectional view of the bracket taken on the line 4—4 of Fig. 1; and

Fig. 5 is a sectional view of the bracket taken on the line 5—5 of Fig. 1.

I claim:

The ornamental design for a thermometer mounting bracket as shown.

CHARLES W. BRANT.
